BOW DRAWING AND RELEASING DEVICE

Glen C. Klaurens, 10412 Princess Jeanne NW.,
Albuquerque, N. Mex. 87112

Filed Oct. 1, 1965, Ser. No. 87,257

Term of patent 3½ years

(Cl. D30—1)

FIGURE 1 is a perspective view of a bow drawing and releasing device showing my new design; and

I claim:

The ornamental design for a bow drawing and releasing device, as shown and described.
